METHOD OF FRACTURING FORMATIONS
Lloyd E. Elkins, Tulsa, Okla., assignor to Pan American Petroleum Corporation, Tulsa, Okla., a corporation of Delaware

Filed Feb. 20, 1959, Ser. No. 794,569
10 Claims. (Cl. 166—42)

This invention relates to an improved method of horizontally fracturing formations. More particularly, this invention relates to a method of hydraulically fracturing subterranean formations wherein long horizontal fractures are selectively produced.

Permeable formations penetrated by a well have been fractured by the application of a high hydraulic pressure in the well as disclosed in Re. 23,733, reissued to Riley F. Farris on November 10, 1953. While that process, as previously disclosed and practiced, normally produces horizontal fractures, i.e., fractures along bedding planes intersected by the well, occasionally a vertical fracture, i.e., a fracture longitudinally of the well, is produced. Vertical fractures are in some instances desirable, but generally they are undesirable, particularly when they extend vertically into water or gas producing horizons adjacent a fractured oil producing formation. It has now been found that a horizontal fracture can to a large extent be selectively produced by minimizing the vertical forces on the formation to be fractured, i.e., by reducing to a minimum the effective overburden pressure on that formation, and that the depth or extent of such horizontal fractures can be increased by minimizing these vertical forces on the formation at great distances from a well.

It is an object of this invention to provide an improved method of fracturing formations penetrated by a well. It is a more specific object of this invention to provide a method of selectively producing long horizontal fractures in an elastic formation penetrated by a well. Other objects of this invention will be apparent from the following description in which:

FIGURE 1 is a cross-sectional view of a well showing apparatus and construction for carrying out the steps of this invention, and

FIGURE 2 is a cross-sectional view of the lower end of a well showing a modified construction for carrying out the steps of this invention.

This invention may be described in brief as an improved method for hydraulically fracturing subterranean elastic formations, such as sandstone or limestone, penetrated by wells wherein deeply penetrating horizontal fractures are selectively produced by substantially reducing over a large area surrounding such wells the effective overburden pressure on the formation to be fractured as the fracturing fluid is injected into that formation. This overburden pressure is reduced by producing a cavity or otherwise enlarging or undercutting a well in a zone which encompasses or spans a plastic formation such as shale that is adjacent to the elastic formation to be fractured. The cavity is then cased off or otherwise isolated from the remainder of the well to maintain a relatively low hydrostatic pressure therein as the fracturing liquid is injected into the elastic formation under a substantially greater pressure—a pressure great enough to fracture the elastic formation.

Referring now to FIGURE 1 of the accompanying drawing for a more detailed description of this invention, a well 10 extends from the surface 11 down through a number of subsurface formations including a plastic formation 12 such as a salt or shale formation and into a permeable elastic formation 13 which is to be fractured.

It has now been found that when a shale formation

2

is confined, the shale performs like an elastic rock, and that when not confined, the shale becomes plastic and flows. An important aspect of this invention is in the discovery that the area of plastic flow in a substantially horizontal plane is proportional to the cross-sectional area in the same plane of a hole or cavity in a shale bed. A well is therefore completed as shown in both FIGURES 1 and 2 in such manner that the shale or other plastic formation 12 has considerable room for flow so that it will be relaxed a great distance from the well. As the well is being drilled or at least during completion of the well, one or more cavities 14 are produced in plastic formations which have been located by driller's logs or the like and are adjacent formations to be fractured. These cavities which typically are produced by underreaming the well are generally therefore coaxial with the well and have an area from two to about ten times or more greater than the area of the well. An underreamed hole about four feet in diameter is typical. Since the height or thickness of the cavity appears to have no effect upon the producing of fractures, it may be varied over a substantial range depending upon the method and apparatus used to produce the cavity. The cavity is generally produced with a mechanical underreamer of the expanding blade or cutter type. Washing or jetting with liquid or abrading with solids in a fluid are alternates. Such cavities, whether formed by these methods or by others, can be produced either while drilling the well or after the well is completed. Where the plastic formation is subjacent and preferably immediately below the formation to be fractured as shown in FIGURE 2, the well may be drilled, a casing 15 run therein and set with a sheath of cement 16 in or through the elastic formation 13 before the cavity is formed below the lower end of the casing. In most cases a cavity is formed in a plastic formation superjacent and preferably immediately above the elastic formation to be fractured as shown in FIGURE 1. Such cavities are, of course, formed prior to running and setting of the casing or a liner therein so that the cavity can be isolated from the well and particularly from the conduit such as the casing through which the fracturing fluid is injected into the well. In either case the casing may be set in the upper part of the producing zone, i.e., the elastic formation 13, using the open hole completion process or technique. With an open hole completion a bridging plug or formation packer (not shown) is in the embodiment of FIGURE 2 set in the well below the casing to isolate the well and a subjacent cavity. Typically casing is set through the producing zone and a number of perforations 17 are placed therein opposite the particular zone or zones of the elastic formation 13 which are to be fractured horizontally. The fluid in the casing is then in the apparatus shown in FIGURE 1 isolated from the cavity by a section 18 of the cement sheath between the perforations and the cavity. In the apparatus shown in FIGURE 2 the fluid in the casing is isolated via the inside of the casing from the cavity by closing the end of the casing as by a bridging plug 19 set in the casing below the perforations 17. On the outside of the casing, in the latter case, the section 18 of cement sheath below perforations 17 and the cementing basket 21 fixed to the lower end of the casing prevent the fracturing fluids leaving the casing via the perforations from bypassing through the well directly to the cavity 14.

In operation, after the plastic formation 12 has been located by cuttings analysis, driller's log, electric log, or the like, and particularly after the shale-permeable formation interface 22 has been located, the cavity 14 is produced and the well apparatus, including a pump 23 connected to discharge into the casing, is installed

as above described. When the cavity is produced, the overburden pressure being greater than the pressure of the fluid in the well, this shale or plastic formation 12 at least partially relaxes, i.e., flows toward the well to decrease the volume of the cavity, simultaneously reducing the vertical stress in the plastic shale for a substantial distance radially into the formation. In some cases after the cavity is produced, liquid is removed from the well to accelerate this flow of the plastic formation into the well. This movement of the shale and the resulting reduction of the vertical stress, i.e., the effective overburden pressure, thus either initiates a fracture at the interface 22 or, due to the reduction of this effective overburden pressure at that interface, causes a fracture 24 to be initiated at a relatively low pressure when hydraulic pressure is subsequently applied to an adjacent zone in the permeable elastic formation 13. While I do not wish to be limited to any theory of operation, it appears that in some cases the movement of the shale into the well produces shear at the interfaces, e.g., interface 22, between a shale zone and an adjacent rock formation, the greater the area of the cavity the greater the area of shear, so that a fracture is not only initiated at the interface but is extended deep into the strata surrounding the well.

After the well and the cavity or cavities have been completed and sufficient time has elapsed, e.g., a day or more, for the plastic formation to approach equilibrium, a quantity of fracturing fluid is injected via pump 23, casing 15, and perforations 17 into the permeable elastic formation 13. This fracturing fluid enters any horizontal fractures initiated by the previous relaxation and movement of the shale or otherwise places the elastic formation 13 under sufficient stress to produce or otherwise extend horizontal fracture 24 deep into elastic formation 13. Formation props 25 carried in the fracturing fluid are thereby placed in the fracture and remain there when the job is completed so that when the well is placed on production and fluid flows from the permeable elastic formation into the well, a highly 40 permeable path is provided.

From the foregoing it can be seen that this invention is susceptible of a wide variety of embodiments and should, therefore, be construed not to be limited by the above description but should be construed to be limited only by the scope of the appended claims.

I claim:

1. A method of producing a long horizontal fracture in a subterranean elastic formation which is penetrated by a well and which is adjacent a plastic formation comprising undercutting said plastic formation to produce a cavity therein having a cross-sectional area substantially larger than that of said well, isolating said cavity from fluid communication with said well by running a casing into said well and into said elastic formation, pausing for a period of time sufficient to permit relaxation of vertical stresses in said plastic formation, perforating said casing at a level opposite said elastic formation, and injecting a fracturing fluid through said well into said elastic formation via the resulting perforations under sufficient pressure to fracture said elastic formation.

2. A method of producing a long horizontal fracture in a subterranean elastic formation which is penetrated by a well and which is adjacent a plastic formation comprising undercutting said plastic formation to produce a cavity therein substantially coaxial with but larger than said well, running a casing into said well, cementing said casing in said elastic formation with the inside of said casing isolated from and out of fluid communication with said cavity, perforating said casing opposite said elastic formation so that the inside of said casing is in fluid communication with said elastic formation; pausing for a period of time sufficient to permit relaxation of vertical stresses in said plastic formation

and selectively injecting a fracturing fluid into said elastic formation through a perforation in said casing under sufficient pressure to fracture said elastic formation.

3. A method of producing a long horizontal fracture in a subterranean elastic formation which is adjacent a plastic formation comprising drilling a well into both said elastic formation and said plastic formation, undercutting said well in said plastic formation to produce a section of enlarged diameter, isolating a zone of said well within said elastic formation from fluid communication with said section of enlarged diameter, pausing for a period of time sufficient to permit relaxation of vertical stresses in said plastic formation said zone being isolated by running a casing into said well and into said elastic formation, perforating said casing at a level opposite said elastic formation, and injecting a fracturing liquid through said well into said isolated zone under sufficient pressure to fracture said elastic formation.

4. A method of producing a long horizontal fracture in a subterranean elastic formation which is penetrated by a well and which is subjacent a plastic formation comprising undercutting said plastic formation to produce a cavity therein, setting a casing in said well through said cavity to isolate fluid in said casing from said cavity, pausing for a period of time sufficient to permit relaxation of vertical stresses in said plastic formation, perforating said casing at a level opposite said elastic formation and then selectively injecting a fracturing fluid through said well into said elastic formation via the resulting perforations under sufficient pressure to fracture said elastic formation.

5. A method according to claim 4 wherein said plastic formation is undercut radially from said well to produce a cavity substantially coaxial with but larger than said well.

6. A method according to claim 5 including perforating said casing opposite said elastic formation and injecting said fracturing fluid into said plastic formation through a perforation.

7. A method of producing a long horizontal fracture in a subterranean elastic formation which is penetrated by a well and which is superjacent a plastic formation comprising undercutting said plastic formation to produce a cavity therein, setting a well casing in said elastic formation, isolating fluid in said casing from said cavity, pausing for a period of time sufficient to permit relaxation of vertical stresses in said plastic formation perforating said casing at a level opposite said elastic formation and then selectively injecting a fracturing fluid through said well into said elastic formation via the resulting perforations under sufficient pressure to fracture said elastic formation.

8. A method according to claim 7 wherein said well casing is set and cemented substantially through said elastic formation including perforating said casing opposite said elastic formation and injecting said fracturing fluid through casing perforations into said elastic formation.

9. A method according to claim 8 including setting a bridging plug in said casing at an elevation below the elevation of said casing perforations to isolate the fracturing fluid in said casing from said cavity and thereby maintain a relatively low fluid pressure in said cavity during injection of said fracturing fluid into said elastic formation.

10. A method according to claim 9 wherein said undercutting of said plastic formation is conducted radially from said well to produce a cavity substantially coaxial with but larger than said well.
